CLAIM

The ornamental design for a pillowcase, as shown and described.

DESCRIPTION

FIG. 1 is a perspective view of the pillowcase;
FIG. 2 is a front elevational view of the pillowcase;
FIG. 3 is a rear elevational view of the pillowcase;
FIG. 4 is a right side elevational view of the pillowcase;
FIG. 5 is a left side elevational view of the pillowcase;
FIG. 6 is a bottom plan view of the pillowcase;
FIG. 7 is a top plan view of the pillowcase;
FIG. 8 is a perspective view of another embodiment of a packaged pillowcase;
FIG. 9 is a front elevational view of the pillowcase;
FIG. 10 is a rear elevational view of the pillowcase;
FIG. 11 is a right side elevational view of the pillowcase;
FIG. 12 is a left side elevational view of the pillowcase;
FIG. 13 is a bottom plan view of the pillowcase; and,
FIG. 14 is a top plan view of the pillowcase.

The broken lines shown in the FIGS. are included for the purpose of illustrating environmental elements only and form no part of the claimed design.
